US00D424003S

United States Patent [19]

Steinhagen

[11] Patent Number: Des. 424,003

[45] Date of Patent: ** May 2, 2000

[54] LICENSE PLATE FRAME

[75] Inventor: Thomas Steinhagen, West Des Moines, Iowa

[73] Assignee: Cobbs Manufacturing Co., Des Moines, Iowa

[**] Term: 14 Years

[21] Appl. No.: 29/106,946

[22] Filed: Jun. 25, 1999

[51] LOC (7) Cl. 12-16

[52] U.S. Cl. D12/193

[58] Field of Search D12/193; D6/300-303, D6/310-313, 314; 40/200-203, 207-210
